FIG. 1 is a front perspective view of a livestock feed scoop with scale reader, showing my new design;
FIG. 2 is a front elevation view thereof;

FIG. 3 is a left side elevation view thereof;

FIG. 4 is a right-side elevation view thereof;

FIG. 5 is a rear elevation view thereof;

FIG. 6 is a top plan view thereof; and,

FIG. 7 is a bottom plan view thereof.

The broken lines shown are included for the purpose of illustrating portions of the livestock feed scoop with scale reader that form no part of the claimed design.

1 Claim, 7 Drawing Sheets
